UNITED STATES PATENT OFFICE.

IRA C. BUCKMINSTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

BLANK-TREATING MACHINE.

Application filed March 8, 1920. Serial No. 364,174.

To all whom it may concern:

Be it known that I, IRA C. BUCKMINSTER, a citizen of the United States, residing at Beverly, in the county of Essex and State 5 of Massachusetts, have invented certain Improvements in Blank-Treating Machines, of which the following description, in connection with the accompanying drawings, is a specification, like reference characters 10 on the drawings indicating like parts in the several figures.

This invention relates to blank treating machines and the machine herein shown and described for the purpose of illustrating 15

one embodiment of the invention is especially designed for operating upon the top lifts of boots and shoes, although it will be apparent that many of the novel features of the invention are not limited to 20 such use.

An important object of the invention is to produce a machine to skive off the surfaces of top lifts so that the lifts will be accurately evened; in other words, it is 25 desired that each lift shall be of uniform thickness throughout its entire area. Hitherto heel lifts have been evened on an ordinary splitting machine, but the difficulty has arisen that the forward edge of a 30 lift as it reaches the knife and the rear edge of the end of the lift as it leaves the rolls have been beveled off somewhat so that the lifts have not been satisfactorily evened.

A further object is to provide a machine 35 that will perform several operations automatically and thus eliminate handling of the blanks. In the embodiment shown, the machine is organized to feed the blanks from a magazine to an intermittently rotatable table, to clamp them in position on the table, measure them for thickness, 40 skive them and then carry them beneath a discharge magazine where they are expelled and stacked in a pile. In various 45 aspects, however, the invention is not limited to a machine for performing all these operations.

Another object is to provide a feeding 50 magazine to hold blanks when it is detached from the machine and to release the blanks to a feeding device when the magazine is placed in operative position on the machine.

The invention also includes a holder or clamping device which preferably can be adjusted to receive any one of a series of 55 different sized magazines which hold different sized blanks.

A further object is to provide a simple form of feeding device to feed blanks one by one, an important characteristic being 60 that the blanks themselves operate the feeding device directly. The invention also includes novel means for adjusting the feeding device so that it will operate properly with the different sized blanks and magazines. 65

The invention also comprises improved securing means to retain the blanks on a rotatable support or table. Preferably the securing means is automatically operated 70 as by suitable cams as the support or table rotates, the construction being such that the securing means is inoperative when the blanks are fed to the table or expelled therefrom but is operative when the cutting is taking place. Novel means for intermittently rotating the table is also provided. 75

Another object is to provide means to measure the thickness of each blank and then set a cutter in accordance with this 80 thickness. In the preferred embodiment, the machine is organized so that a measuring member engages each blank near the center and then automatically sets the cutter so that the latter will cut in a slightly lower 85 plane than the bottom of the member. Thus, even if the various blanks differ from each other considerably in thickness, approximately the same amount of material will be cut from each. The invention includes also 90 a novel form of presser, an important feature being that this presser is carried by the cutter head and preferably is yieldably and rockably mounted on the cutter head to properly engage an uneven blank and hold 95 it under yielding pressure.

Still another object is to provide novel means whereby further feeding of blanks is prevented when a discharge magazine has 100 been filled with finished blanks. In the preferred construction, an automatic stop device is mounted in the discharge magazine in such manner that it can be moved to inoperative position whenever it is desired.

to remove the magazine with its finished blanks.

Other objects and features of the invention will be apparent upon a consideration of the following specification and claims in connection with the accompanying drawings. Although the machine has been described as adapted for operation on top lifts for leather heels, it is not limited to operation on top lifts nor to leather blanks.

Referring to the drawings,

Fig. 1 is a front elevation of the machine as a whole with some parts in section;

Fig. 2 is a top plan view with parts in section;

Fig. 3. is a section on the line 3—3 of Fig. 1;

Fig. 4 is a fragmentary section on an enlarged scale of the receiving magazine and feeding mechanism, the section being taken on the line 4—4 of Fig. 2;

Fig. 5 is an enlarged section of the knife or cutter and cooperating parts the section being along the line indicated by 5—5 in Fig. 2;

Fig. 6 is an enlarged section of the ejecting mechanism on the line 6—6 of Fig. 2;

Fig. 7 is a fragmentary plan view partly in section of part of the feeding mechanism shown in Fig. 4 the section being on line 7—7 of Fig. 4;

Figs. 8 and 9 are detail sections of the ejecting and feeding mechanisms, respectively, Fig. 8 being on the line 8—8 of Fig. 6 and Fig. 9 being on the line 9—9 of Fig. 4;

Fig. 10 is a perspective view of a detail of the knife setting mechanism;

Fig. 11 is a development of the cams that determine the sequence of the above-mentioned operations;

Fig. 12 shows a plan view of a modified form of clamping device for the heel lifts, including a modified form of cam for releasing the clamping device;

Figs. 13, 14 and 15 are sections taken on the lines 13—13, 14—14 and 15—15 of Fig. 12, respectively.

Referring to the drawings, 2 indicates the frame which in this case carries two complete machines diametrically disposed. Power from a belt is applied to tight and loose pulleys 3 on the shaft 5 which carries a worm 6 to drive a worm wheel 7 on a vertical shaft 8. The shaft 8 carries a cam member 9 with four cam slots which operate the measuring, cutting, feeding and ejecting mechanisms, respectively. For rotating the support or table 10 intermittently, the shaft 8 carries, at its upper end, two cranks 11 and 12, the upper crank 11 being pivotally connected by a link 13 to an upper ring 15 and the lower crank being pivotally connected by the link 14 to a lower ring 16 (see Figs. 1, 3 and 6). These two rings 15

and 16 surround the sleeve 17, integral with, and depending from the table 10 and each ring pivotally carries a spring pressed pawl 18 which in turn engages with teeth 19 disposed at intervals around the table sleeve 17 keyed to the latter. There are six teeth on the table spaced 60° apart and one pawl 18 on each ring, the two pawls being spaced 60° apart. It will be apparent that rotation of the shaft 8 will cause rotation of the table intermittently through the described parts. The two cranks 11 and 12 are diametrically arranged and consequently there are two positions at which their crank pins will be at dead centers with reference to the shaft 8 and the pivots between links 13, 14 and the rings 15, 16. At these positions, the table is stationary and it is then that the operations of feeding, cutting and ejecting occur. The number of teeth may of course be varied, depending on the number of machines disposed around the center line.

Referring to Figs. 4 and 9, there is shown a lift feeding magazine 20 detachably mounted in a holder 21, 21', adjustably supported in a yoke or bracket 22 and overlying the rotatable table. Each feeding magazine 20 carries spring pressed catches 23 which normally support, in the magazine, a series of heel lifts but these catches are designed to release the lifts automatically when the lugs 23' on the catches engage the holder 21, 21'. The lifts then drop into the lower portion of the holder as indicated in Fig. 4. It is intended that different sized magazines shall be used for different sized lifts and the holder 21, 21' is therefore made adjustable to accommodate the different magazines. This adjustment is effected by the following appliances. (See Figs. 2, 4 and 6.) A threaded stud 24 secured to the holding member 21 passes loosely through the yoke or bracket 22 and carries a knurled nut 25 which is threaded both inside and out but one thread is right and the other left. The nut is held against longitudinal movement by an integral collar 26 engaging behind lugs 27 on the yoke or bracket 22.

Referring to Fig. 2, the exterior threads on the nut 25 engage the threaded extremities 28 of bell crank levers 29 pivotally mounted on the yoke at 30. The arm 31 of each bell crank lever is slotted to receive a pin 32 projecting radially from a rod 33 slidably mounted in the slotted sleeve 34 on the yoke 22. The rod 33 carries the holding member 21' which is operated simultaneously with the holding member 21 upon rotation of the nut 25, as is obvious. The holding member 21 engages the breast of the heel lifts and has horizontal lugs 35 to support the lifts. The holding members 21' engage the curved sides of the heel lift and have horizontal supporting lugs 36. The

holding members 21' are cut away near the bottom at 37 (see Fig. 4), adjacent the curved sides of the lowermost lift in order to allow the lift to be fed, but they extend 5 low enough to aid in retaining the second lift in position. The holding member 21 is curved where engaged by the breast of each lift in order to position the series of lifts in overlapping relation.

10 The feeding mechanism for feeding the blanks one at a time is shown at the right of Fig. 4 and includes a sliding feed controlling finger 41 and a sliding and swinging feed controlling finger 40 both of which 15 are adjustably mounted with reference to the feeding magazine 20. The finger 40 is 20 slideable in guideways 42 on a carrier 43 which is pivoted at 44 on an adjustable bracket 45. The bracket 45 is slotted at 46 and is provided with a clamp nut 47 which 25 will hold it in adjusted positions along the guideways 48 in the yoke 22. The finger 40 is pivoted at 49 to a lever 50, this lever being pivoted loosely at one end at 51 to 30 the bracket 45 and being pivoted near its middle at 52 to the carrier 43. The swinging of the carrier 43 on its pivot 44 will obviously act to raise and lower the sliding finger 40 and the carrier will also impart its own swinging motion to the finger.

The finger 41 slides vertically in guideways 42' fixed to the bracket 45, the sliding action being produced by a second lever 53 pivoted at 54 to the carrier 43. This lever 35 is loosely pivoted at 55 near its middle to the bracket 45, and its inner end is connected to the upper end of finger 41 by a coil spring 56. This coil spring tends to pull the finger 41 down against a stop collar 57 fixed to a rod 58. The rod is pivoted to the lever 53 and passes loosely through a lug on the upper end of the finger 41 and acts to raise it positively. The swinging of the carrier 43 will obviously impart a swinging action to the lever 53 which will in turn 40 raise or lower the finger 41. The finger 41 and guideway 42' have cut out portions to allow the lever 53 and the finger 40 to swing freely to the dotted line positions shown in Fig. 4 without interference. A 45 spring 59 acts against an abutment to restore the swinging carrier 43 to normal position after it has been moved in the feeding operation.

50 A horizontally reciprocating feed member or dog 60 pushes the lowermost lift against the finger 40 and this swings the carrier 43 about its pivot 44. The pivot 52 will be raised and likewise the pivot 49 55 to a greater extent, thus raising the finger 40 to allow the lowermost lift to pass. The pivot 54 will be raised, thus swinging the lever 53 on its pivot 55 and lowering the slide finger 41. The finger 41 will engage the top surface of the lowermost blank and

the spring 56 will allow the finger to yield in case a thick blank is encountered. The finger 41 will thus prevent the feeding of the second blank, whatever its thickness. The spring 59 then restores the carrier to 70 normal position with the finger 40 against the edge of the lowermost blank.

75 As shown in Fig. 1, the dog 60 is supported on substantially parallel links 61, 62 pivoted to the frame at 63, and 64 respectively. A horizontal motion is imparted to these links and the feed dog by an arm 65 whose slotted end 66 removably engages a pin 67 on a crank 68. This crank is mounted on one end of a shaft 69 supported in bearings on the frame, and the other end of the shaft carries an arm 70 having a cam following roller 71 adapted to engage the cam surface 72 on the cam 9.

80 The lifts are pushed out one by one onto the rotatable table 10 where they are gripped at the rear by plates 80 (Fig. 4) and at the breast part by a sliding clamp plate 81 pressed towards the lift by a spring 82. The plate 81 cannot move however, until 85 the table rotates sufficiently to enable the pin 83 to pass off the cam surface 84. (See Figs. 3, 4 and 6). This cam surface 84 is fixed and is secured to a depending bracket 85 carried by the yoke 22. The 90 plates 80 and 81 are undercut to aid in gripping the lift and in holding it down.

95 With the lift secured on the table, the latter rotates until the lift comes beneath the measuring and cutting device shown in 100 Fig. 5. The cutter head 90 has an integral sleeve 91 to the upper end of which a belt pulley 92 is secured. The pulley 92 is driven by a belt from the pulley 4 on the main drive shaft 5, the belt also passing over pulleys 93 and 94. The cutter head 90 has downwardly opening sockets 95 containing pins 96 which are secured to the presser plate 97. The pins 96 are loose in the sockets 105 and are carried by bolts 98 which pass through openings in the sockets and springs 99 allow the pins and presser plate 97 to yield or rock somewhat when an uneven lift is encountered. The cutter head 90 carries a knife or cutter 100 shown best 110 in Fig. 3 and in dotted lines in Fig. 5. This knife 100 extends obliquely through slots in the cutter and in the presser plate to engage the blank; the knife could, if desired, be formed integrally with the member 90.

115 The cutter head 90 is raised and lowered with a sleeve 101 which rests against the pulley 92 at its upper end and engages a thrust bearing 102 at its lower end. For 120 operating the sleeve 101, a bifurcated lever 103 (see Fig. 1) is pivoted to a fixed pivot 104 and is connected to the sleeve 101 by pivot bolts 105. The inner end of the lever 103 is pivoted at 106 to a block 107 through 125 which passes a rod 108 having a stop collar 130

at the upper end. The lower end of the rod 108 is secured to a slotted block 109 which slides in guides 110 on the frame. A stiff coil spring 111 normally presses the block 107 against the stop collar and yieldingly 5 forces the cutter downwardly when such action is permitted under conditions to be described.

The distance which the cutter is depressed 10 is determined by a measuring rod or cutter setting device 120 which extends down through the cutter head and engages the top face of the heel lift. The rod 120 is loosely pivoted at its upper end to a lever 121, the 15 lever having a pivot support at 122 on a bracket 123. An arm 124 is formed integrally with the lever and is connected with the bracket 123 by a spring 125 so that the measuring rod is normally pressed downwardly. The position of the rod determines 20 the position of the knife in the following way:—The lever 121, at its lower end, has a fork 130 with inwardly directed pins 131 engaging in slots 132 in a wedge member 25 133 (shown in detail in Fig. 10). The wedge member 133 is forked and slides between the sleeve 101 and a fixed casing 134; the position of the wedge will obviously determine the amount the cutter head can descend. The wedge member has guides 135 30 to engage and slide on guideways 136 on the casing 134. (See Figs. 5 and 10). The wedge has also at one side a projecting plate 137 with teeth 138 thereon. These teeth 35 co-operate with a pivoted pawl 139 to lock the wedge to hold the measuring rod raised. The pawl is normally pressed into action by a spring 140 but it can be released at the proper time by a lever 141 pivoted to the 40 frame at 142.

Before the measuring rod can descend, the pawl must be released and, for this purpose, the lever 141 is pivotally connected at 45 143 to a cross rod 144 (see Fig. 1). One rod 144 operates two sets of levers, pawls, etc. as shown, and is connected to bell crank 145 pivoted to the frame at 146. The bell crank is connected by links 147 to lever 148 and the latter has a cam roller on one end to engage a cam 150 on the cam shaft 8.

For restoring the wedge 133 to raise the measuring rod or cutter setting device, the lever 141 has an arm 151, which at a time determined by the cam 150, will engage 55 the fork 130 and push the wedge inwardly where it will be locked by the pawl 139.

The cutter head is controlled by a cam 160 on cam shaft 8. The cam engages a roller follower on the lever 162 and a link 60 163 connects lever 162 with bell crank 164. The latter is pivoted on the frame at 165 and has one arm connected by a rod 166 with a toggle 167. When the toggle links are straightened, the block 109, previously 65 described, is free to rise in the guide 110

and the spring 111 causes the cutter to descend. Conversely, breaking the toggle will raise the cutter head so that the wedge can be subsequently operated to raise the measuring rod.

70

The cutter head and knife revolve rapidly at all times, and, when the measuring rod has engaged the middle of the heel lift, the knife is arranged to come a trifle lower in order to skive off the lift. A small part 75 of the surface in the middle of the lift will not be cut at first because the cutting surface of the knife extends inwardly only to the periphery of the rod. However, as soon as the lift is carried around slightly by the 80 table, the center of the lift will also be skived off even with the outer portions.

75

The next operation is that of ejecting the skived lifts. (See Figs. 5 and 6). The lift, as it leaves the cutter, is in a clamped position on the table due to its engagement with plates 80 and 81. To release the lift when it arrives beneath the discharge magazine 170, the fixed cam 84 engages the pin 83 and pushes it to the left as viewed 85 in Fig. 6; this releases the lift, whereupon a plunger pushes it up into the magazine 170. This magazine 170 is similar to the magazine 20 but carries a spring pressed 90 catch 171 (see Fig. 8) having a beveled 95 lip 172, the bevel being engaged by the lift to turn the catch on its pivot in order to allow the lift to rise in the magazine.

95

To expel the lift, a cam controlled plunger or ejector 173 is provided (see Figs. 5 and 100 6); it has projecting pins 174 sliding in slots in a socket or sleeve 175 secured to the table 10. The plunger is normally held down by a forked leaf spring 176 attached to the table and engaging the pins 174. The 105 plunger is lifted automatically by the arm 177 (see Figs. 1 and 6) which has bifurcations engaging the pins 174. The arm is pivoted to the framework at 178 and is rocked by an arm 179, link 180, arm 181, rock shaft 182 and arm 183 which latter is actuated by the cam surface 186. The arm 177 opposite to arm 177 is connected directly to the arm 183 by a link 185.

110

To prevent further feeding when the magazine 170 is full of lifts, the slotted link 65 is automatically raised from engagement with the pin 67 (see Figs. 1 and 2). This is accomplished by a roller 190 on a rock arm 191 secured to a shaft 192 journaled 120 in the framework. The shaft has a second arm 193 thereon which is connected by a rod 194 with an arm 195 and a disk 196 near the top of the magazine 170. The disk 196 is suspended from the arm 195 by a stem 197 and both disk and arm are raised vertically 125 by the lifts in the magazine as the latter fills up. The arm 195 compresses a coil spring 198 and thus yieldingly raises the rod 194 to automatically disengage the feed 130

130

link 65. The rod 194 slides in a bearing 199 on the framework and has a button 200 swivelled thereon which can be turned to rest on a lug 201 on the bearing 199 to thereby maintain the rod raised and the feed link 65 in non-feeding position. The disk 196 and arm 195 are swung around manually over the top of the magazine 170 when the latter is full and the magazine can then be removed and a like one substituted.

Referring to Fig. 11 a development of the cam surfaces is shown and the sequence of the operations of feeding, measuring, cutting and ejecting is indicated. The timing can of course be varied as conditions necessitate.

Referring to Figs. 12 to 15, a modified form of clamping device for the lifts is shown. A series of clamping lugs 211 having downwardly extending studs 212 are mounted on the table 10 to slide radially with reference to the center of the ejector. The studs 212 are guided in radial slots 213 in the table 10. The studs 212 project below the radial slots into a series of spiral slots 217 in a cam plate 214 which is secured between the table 10 and a spanner nut 216; the spanner nut is screwed onto the outer surface of the ejector socket 175 and bears against a shoulder on the socket. The plate 214, with its spiral slots, acts as a cam to force the clamping lugs outwardly and inwardly in the radial slots, and a spring 220, attached at one end to a stud 218 on the table, and at the other end to an arm 219 on the plate 214, normally holds the plate in a position to clamp the lift.

As the table rotates, the clamping lugs will be simultaneously released when the adjustable bolt 222 carried on the lug 221 engages a cam surface 224 on an interrupted ring member 223. The ring member 223 is supported by the bracket 85 on the yoke 22. The head of the bolt 222 rides on the incline 224 and retracts the clamping lugs 211, the lugs remaining in unclamped position as long as the bolt 222 remains in contact with the interrupted ring member 223.

The operation will be apparent from a careful reading of the above but briefly the action is as follows: A magazine full of lifts is placed in position as shown in Fig. 4 and the feed dog pushes them out one at a time upon the intermittently rotating table where they are clamped in position and carried under the knife. (See Fig. 5). The measuring rod descends upon the lift and determines the position to which the cutter may descend in accordance with the thickness of the lift. The cutting takes place, the table rotates again and carries the lift to the ejecting position where it is automatically released and then pushed up into the discharge magazine. When the latter is full, the feed is automatically cut off.

Two complete machines are shown; they are substantially duplicates and are diametrically disposed but the device is not limited to any particular number of machines although a plurality of machines is better adapted to secure readily a compact and convenient assembly to economize space and renders unnecessary a complete duplication of all the parts.

Having described my invention, what I claim as new and desire to secure by Letters Patent of the United States is:

1. In a blank treating machine, a feed magazine, a rotary table, means to feed blanks one by one from the magazine to the rotary table, means to secure the blanks on the rotary table, means to measure the blanks and skive them while secured on the rotary table, and means to transfer the blanks from the rotary table to a stacking magazine.

2. In a blank treating machine, a feed magazine, a rotary table, means to feed blanks one by one from the magazine to the rotary table, means to secure the blanks on the rotary table, means to skive the blanks while secured on the rotary table, and means to transfer the blanks from the rotary table to a stacking magazine.

3. In a blank treating machine, a feed magazine, a rotary table, means to feed blanks one by one from the magazine to the rotary table, means to skive the blanks while supported on the rotary table, and means to transfer the blanks from the rotary table to a stacking magazine.

4. In a blank treating machine, a rotary table, a feed magazine at one station, means to feed blanks one by one from the magazine to the rotary table, and means at another station to skive the blanks while supported by the rotary table.

5. In a blank treating machine, a rotary table, a feed magazine at one station, means to feed blanks one by one from the magazine to the rotary table, and means at another station to measure and skive the blanks while supported by the rotary table.

6. In a blank treating machine, a rotary table, a feed magazine at one station, means to feed blanks one by one from the magazines to the rotary table, means operable automatically as the table rotates, to secure the blanks on the table, and means at another station to skive the secured blanks.

7. In a blank treating machine, a rotary table, a feed magazine at one station, means to feed blanks one by one from the magazine to the rotary table, means operable automatically as the table rotates, to secure the blanks on the table, and means at another station both to skive and measure the secured blanks.

8. In a blank treating machine, a support for blanks, means for measuring the thickness of a blank while resting on the support,

- and means for skiving the blank while the latter retains its position relatively to the support. 17. In a blank treating machine, a support for blanks, a hollow cutter head, and means including a rod passing through the cutter head to engage a supported blank and to set the cutter head in accordance with the thickness of the blank. 65
9. In a blank treating machine, an intermittently movable support for blanks, means for measuring the thickness of a blank when the support is stationary, means for skiving part of the surface of the blank in the measuring position and subsequently skiving the remainder of the surface of the blank when the support moves. 10. In a blank treating machine, a rotary table, means to feed blanks one by one to the rotary table, and a rotary knife to operate on the blanks while supported on the rotary table. 15. 11. In a blank treating machine, a movable support, means to feed blanks one by one to the movable support, means to measure the blanks while on the movable support, a knife to operate on the blanks while on the movable support and connections between said knife and measuring means for adjusting the former from the latter. 20. 12. In a blank treating machine, a movable support, means to feed blanks one by one to the movable support, means to measure the blanks while on the movable support, and a knife located at the same station as is the measuring means and adapted to operate on the blanks in the measuring position. 25. 13. In a blank treating machine, a movable support, means to feed blanks one by one to the movable support, blank securing means operable by motion of the support, and a rotary knife to operate on the blanks in their supported and secured positions. 30. 14. In a blank treating machine, a movable support, means to feed blanks one by one to the movable support, blank securing means operable by motion of the support, means to measure the blanks while on the support, and a knife to operate on the blanks, said knife being set by the measuring means. 40. 15. A machine of the class described having, in combination, a support for a blank, a cutter for evening the blank adjustable toward and from the support, mechanism for measuring the thickness of the blank, and means for adjusting the cutter in accordance with the determination of the measuring mechanism. 50. 16. A blank treating machine having, in combination, a support for blanks of different thicknesses, a cutter adjustable toward and from the support, and means including a measuring member movable by contact with the blank with respect to the cutter for adjusting the cutter into a position dependent upon the thickness of the blank at the locality engaged by the measuring member. 60. 17. In a blank treating machine, a support for blanks, a rotary cutter, means to move the cutter axially, and means to engage a supported blank to predetermine the position to which the cutter shall move. 75. 18. In a blank treating machine, a support for blanks, a cutter, a measuring rod to engage a supported blank, and a wedge connected to the measuring rod to determine the ultimate position of the cutter. 80. 19. In a blank treating machine, a support for blanks, a cutter, a measuring rod to engage a supported blank, a wedge connected to the measuring rod, means to lower the cutter to a position determined by the position of the wedge, and means to raise the measuring rod and to lock the wedge. 85. 20. In a blank treating machine, a support for blanks, a cutter, a measuring rod to engage a supported blank, a wedge connected to the measuring rod, means to lower the cutter to a position determined by the position of the wedge, and means to raise the measuring rod and to lock the wedge. 90. 21. In a blank treating machine, a vertically movable cutter, a measuring rod, means connected to the rod to determine the distance the cutter shall descend, means to raise the cutter, and means to raise the rod. 95. 22. In a blank treating machine, a movable cutter, means to raise and to lower the cutter, means to determine the lowermost position of the cutter, a lock for said means, and releasing means for the lock. 100. 23. In a blank treating machine, a support for blanks, a movable cutter, means to raise and to lower the cutter, a rod to engage a supported blank, a lever secured to the rod, and means connected to the lever to limit the lowermost position of the cutter. 105. 24. A blank treating machine having, in combination, a support for the work, a cutter, yielding means for urging the cutter toward the support, an adjustable stop for limiting such movement, and measuring means arranged to contact with the work and to adjust the stop in accordance with the thickness of the work. 110. 25. A machine for evening blanks having, in combination, a substantially flat support for a blank, a rotary cutter the plane of the cut of which is substantially parallel to the plane of the support, means for adjusting the cutter yielding into a position parallel to but spaced from the support, means for causing relative movement between the cutter and the support in a direction transverse to the direction of the adjusting movement to cause the blank to be evened, and means acting automatically to raise the cutter at the end of the evening operation. 115. 26. In a blank treating machine, a cutter, means for rotating the cutter, a lever to raise and lower the cutter, a toggle to con- 120. 125.

trol the lever, and means for intermittently actuating the toggle.

27. In a blank treating machine, a cutter, means for rotating the cutter, a spring tending at all times to move the cutter into operative position, a toggle, and means for operating the toggle intermittently to compress the spring and withdraw the cutter from operative position.

10 28. A machine for evening blanks comprising a substantially flat support for a blank, a rotary cutter the plane of the cut of which is substantially parallel to the plane of the support, automatic means for 15 adjusting the cutter into a position dependent upon the thickness of the blank and means for producing relative movement between the support and cutter in a direction to cause the blank to be traversed by the 20 cutter.

29. In a blank treating machine, a movable support, a sliding clamp plate on the support, a spring to close the clamp plate, and a fixed cam to open the clamp plate 25 against the tension of the spring and to subsequently allow the spring to close the clamp plate.

30. In a blank treating machine, a movable substantially flat support, a sliding clamp plate on the support, a feeding station, an ejecting station, a spring to close the clamp plate as the blank leaves the feeding station, and a fixed cam at the ejecting station to open the clamp plate against 35 the tension of the spring.

31. In a blank treating machine, a movable substantially flat support, blank clamping means on the support, a feeding station, an ejecting station, a fixed cam at the feeding station to open the clamp as the latter reaches the feeding station, a spring to close the clamp as the latter leaves the feeding station, and a fixed cam at the ejecting station to open the clamp against the tension 45 of the spring.

32. In a blank treating machine, a movable support, a clamp plate fixed on the support, a slidable clamp plate on the support, a spring to close the slidable clamp plate, and a fixed cam to open the slidable clamp plate 50 against the tension of the spring.

33. In a blank treating machine, a support for blanks, an axially movable rotary cutter head to operate on the supported blanks, and a rockably mounted presser plate carried by the cutter head.

34. In a blank treating machine, a rotatable cutter head and a presser plate rockably carried by the cutter head to engage the top face of an uneven blank to hold it while being cut.

35. In a blank treating machine, a cutter head, a presser plate, spring pressed plungers loosely mounted on the cutter head, and

connected to the presser plate whereby the latter may yield and rock when in engagement with a blank.

36. In a blank treating machine, a rotary cutter head having a slot therein, a presser plate located below the cutter head and rotatable therewith, said plate having a slot to register with that of the cutter head, and a knife secured in the slot of the cutter head and extending through the slot in the presser plate.

37. In a blank treating machine, a slotted cutter head, a slotted presser plate yieldably carried by the cutter head, and a knife secured in the slot of the cutter head and adapted to extend through the slot in the presser plate when the latter engages a supported blank.

38. In a blank treating machine, a cutter head, a slotted presser plate yieldably carried by the cutter head, and a knife secured to the cutter head and adapted to extend through the slot in the presser plate when the latter engages a supported blank.

39. In a blank treating machine, a magazine holder adjustable to receive different sized magazines, blank supporting means carried by the holder below the magazine, and feeding mechanism adjustable with reference to the supported blanks.

40. In a blank treating machine, a bracket, a magazine holder adjustable on the bracket to hold different sized magazines, and feeding mechanism adjustable with reference to the holder and its supported magazine.

41. In a blank treating machine, a magazine holder adjustable to receive different sized magazines, and means carried by the holder below the magazine to support the blanks when released from the magazine.

42. A machine for evening blanks, comprising a substantially flat support for a blank, means for pressing the blank against the support, a cutter the plane of the cut of which is substantially parallel to the plane of the support, and means for moving the support and with it the blank past the cutter.

43. A machine for evening blanks, comprising a substantially flat support for a blank, means for clamping the blank upon the support, means for pressing the blank against the support, a rotary cutter the plane of the cut of which is substantially parallel to the plane of the support, and means for moving the support and with it the blank past the cutter.

44. In a blank treating machine, an adjustable holder for magazines of different sizes including a breast engaging member, side engaging members, levers connected to the side engaging members, and a nut to engage both the breast engaging member and

the levers to move all the engaging members simultaneously.

45. In a blank treating machine, an adjustable holder for magazines of different sizes including a breast engaging member, a threaded stud secured thereto, side engaging members, levers secured to the latter, a nut threaded on the stud and exteriorly threaded in an opposite direction to engage the levers whereby the engaging members can be moved simultaneously.

46. In a blank treating machine, an adjustable holder for magazines of different sizes including a breast engaging member having a threaded stud mounted slidably in a fixed support, side engaging members each having a rod slidably mounted in a fixed support, bell crank levers pivoted on the fixed support and each connected to one of the rods, a nut threaded on the threaded stud, a collar to hold the nut against axial movement, and threads on the outer surface of the nut to engage the bell crank levers.

47. In a blank treating machine, the combination of feeding means, a discharge magazine, a rod, a rotatable arm on the rod, a stop secured to the arm and adapted to be engaged by the blanks in the discharge magazine as the magazine becomes full, and connections between the rod and the feeding means.

48. In a blank treating machine, the combination of feeding means, a discharge magazine, a stop within the magazine to be engaged by the blanks when the magazine is full, an arm carrying the stop, and connections between the arm and the feeding means.

49. In a blank treating machine, the combination of feeding means, a discharge magazine, a movable stop therein adapted to stop the feed, and means for moving the stop away from the magazine to allow the removal of the latter.

50. In a blank treating machine, the combination of feeding means, a discharge magazine, a stop therein adapted to stop the feed, and a rotatable arm carrying the stop whereby the stop and arm can be swung away from the magazine to allow the removal of the latter.

51. In a blank treating machine, the combination of feeding means, a discharge magazine, a slidable stop in the magazine connected to the feeding means, and means for swinging the stop outside the magazine to allow the removal of the latter.

52. In a blank treating machine, the combination of a feed member, a discharge magazine, a stop inside the magazine adapted to be engaged by the blanks in the magazine when the latter is full, and a connection between the stop and the feed member to stop the latter.

53. In a blank treating machine, the com-

bination of a feed member, a discharge magazine, and a connection between the discharge magazine and the feed member to stop the latter when the magazine is full.

54. In a blank treating machine, a discharge magazine for holding a stack, a stop within the magazine, and means whereby the stop can be moved outside the stack to allow the removal of the latter.

55. In a blank treating machine, a magazine, a feed member, and relatively movable fingers for controlling the feeding of blanks from the magazine, said fingers being operated by the feed member through the medium of the blanks.

56. In a blank treating machine, a magazine, a feed member, and feed-controlling mechanism operated by the feed member, said mechanism including a sliding and swinging finger.

57. In a blank treating machine, a magazine, a feed member, feed-controlling mechanism operated by the feed member, said mechanism including sliding fingers and being adjustable with reference to the feed member to feed different sized blanks.

58. In a blank treating machine, a magazine, a feed member, and feed-controlling mechanism operated by the feed member and adjustable with reference to the feed member to operate on different sized blanks.

59. In a blank treating machine, a magazine, a feed member, feed-controlling mechanism including a swinging carrier having a sliding finger operated by the feed member to swing the carrier in one direction, and a spring to restore the carrier to normal position.

60. In a blank treating machine, a magazine, a feed member, and feed-controlling mechanism including a swinging carrier having a sliding finger operated by the feed member through the medium of the blanks.

61. In a blank treating machine, a magazine having an outlet, means for feeding blanks through said outlet, and mechanism for controlling the number of blanks which can be fed through the outlet at one time, said mechanism including movable fingers extending across said outlet and connections between said fingers such that pressure exerted upon one of the fingers operates both of them.

62. In a blank treating machine, a magazine having an outlet, means for feeding blanks one by one through the outlet and mechanism for preventing the feeding of more than one blank at a time through the outlet, said mechanism including a finger adapted to be swung outwardly to permit the lowermost blank of the stack to be fed, and a second finger adapted to be brought down upon the top of the lowermost blank, and connections between the fingers such

that swinging of the first-named finger outwardly causes the downward movement of the second-named finger.

63. In a blank treating machine, a magazine, feed-controlling mechanism including a swinging carrier, a sliding finger thereon, a second sliding finger, and levers, each pivotally connected with a fixed support, with the carrier and with a sliding finger.

64. In a blank treating machine, a magazine, feed-controlling mechanism including a swinging carrier, a sliding finger thereon, a lever pivotally connecting the finger with a fixed support and with the swinging carrier.

65. In a blank treating machine, a magazine, feed-controlling mechanism including a swinging carrier, a sliding finger thereon, a lever pivotally connected with the finger, with a fixed support and with the swinging carrier, a second sliding finger mounted in

a fixed guideway and a second lever pivotally connected to the carrier, to the fixed support and to the second finger.

66. In a blank treating machine, a rotary support, a drive shaft, oppositely extending cranks thereon, and means connecting the cranks to the support to rotate the latter intermittently.

67. In a blank treating machine, a magazine having an outlet, a feed member, means for operating the feed member to push the blanks through the outlet, relatively movable fingers extending across the outlet and adapted to prevent the feeding of more than one blank at a time through the outlet, said fingers being operated by the feed member through the medium of the blanks.

In testimony whereof I have signed my name to this specification.

IR A C. BUCKMINSTER.
